DESIGN FOR A PLAQUE

George W. Wahrer, Cleveland, Ohio

Application July 12, 1946, Serial No. 131,541

Term of patent 14 years

(Cl. D29—24)

To all whom it may concern:

Be it known that I, George W. Wahrer, a citizen of the United States, residing at Cleveland, in the county of Cuyahoga and State of Ohio, have invented a new, original, and ornamental Design for a Plaque, of which the following is a specification, reference being had to the accompanying drawing, forming a part thereof.

I claim:

The ornamental design for a plaque, as shown.
GEORGE W. WAHRER.
